UNITED STATES PATENT OFFICE.

LEVEY MCCOY, OF MEMPHIS, TENNESSEE.

EMBALMING APPARATUS.

1,031,565.

Specification of Letters Patent.

Patented July 2, 1912.

Application filed November 2, 1911. Serial No. 658,175.

To all whom it may concern:

Be it known that I, LEVEY McCoy, a citizen of the United States, residing at Memphis, in the county of Shelby, State of Tennessee, have invented certain new and useful Improvements in Embalming Apparatus; and I do hereby declare the following to be a full, clear, and exact description of the invention, such as will enable others skilled in the art to which it appertains to make and use the same:

This invention relates to embalming apparatus.

The object of the invention resides in the provision of an embalming apparatus through the instrumentality of which the embalming operation may be performed with comparative ease, very effectively, and with minimum attention.

With the above and other objects in view, the invention consists in the details of construction and in the arrangement and combination of parts to be hereinafter more fully described and particularly pointed out in the appended claim.

In describing the invention in detail, reference will be had to the accompanying drawings wherein, like characters of reference denote corresponding parts in the several views, and in which—

Figure 1 is a perspective view showing the apparatus suspended for use, Fig. 2, a view partly in elevation and partly in perspective showing the manner of supplying fluid to the reservoir of the apparatus, previous to suspending the latter to institute the operation of embalming, Fig. 3, a vertical section through the reservoir of the apparatus, and Fig. 4, a detail perspective view showing the manner of securing the removable bottom of the reservoir in place.

Referring to the drawings, 10 indicates the reservoir of the apparatus which is preferably constructed of glass of the transparent type. This reservoir 10 is surrounded by a metal jacket 11 secured in place in any suitable manner and provided with an opening 12 through which the quantity of fluid in the reservoir may be at all times observed.

To assist in ascertaining the exact amount of fluid in the reservoir the latter between the sides of the opening 12 is provided with scales 13 each of which has a definite designation placed in line therewith upon the jacket 11. The reservoir 10 is provided with an opening 14 in its bottom and an

outwardly directed flange 15 surrounding said opening. Secured against the bottom of the reservoir across the opening 14 is a cap 16 which has extending centrally therethrough and secured thereto a tube 17 one end of which projects into the reservoir and terminates a short distance from the top of the latter, while the other end of said tube is disposed outside of the reservoir. The cap 16 further carries a nipple 18 projecting outwardly with respect to the reservoir and disposed at an inclination to the cap. This nipple communicates at its inner end with the interior of the reservoir and is adapted to receive on its outer end a discharge tube 19, the outer end of which latter carries a needle 20 for insertion into the desired artery of the corpse. The tube 19 is further provided at a suitable point in its length with a screw valve 21 for controlling the flow of embalming fluid therethrough.

In order to bind the cap 16 against the bottom of the reservoir there is hinged to the lower end of the jacket 11 a strap 22 adapted for movement transversely of the reservoir so as to dispose itself across the outer face of the cap 16. Mounted on the lower end of the jacket 16 diametrically opposite from the hinged connection of the strap 22 is a cam latch 23 which is adapted to operate through an opening 24 in the strap 22 and draw the strap firmly against the outer face of the cap, thereby drawing said cap with relatively great pressure against the bottom of the reservoir and producing a fluid tight joint.

The reservoir is adapted to be suspended by means of a bail 25 secured to the upper end of the jacket 11. This bail 25 is employed particularly to suspend the reservoir from a suitable hook and in case such hook is not at hand the reservoir may be suspended from a chair by means of a ring 26 swiveled upon the upper end of the jacket 11.

In order to fill the reservoir 10 with embalming fluid the same is seated upon a suitable support with its bottom up and a supply tube 27 attached to the outer end of the tube 17. The other end of this supply tube 27 is then secured to the outlet of a blow vessel 28, said blow vessel being operated by a suitable air compressor 29. By this construction it will be apparent that when the blow vessel 28 is filled with embalming fluid and the air compressor 29 operated said fluid will be discharged from the blow vessel

through the tubes 27 and 17 into the interior of the reservoir 10. When a sufficient quantity of fluid has been stored in the reservoir 10 the tube 27 is detached from the tube 17 and the reservoir inverted and suspended as shown in Fig. 1 after first closing the valve 21. The needle 20 is then inserted in the desired artery of the corpse and the valve 21 regulated so as to permit the proper flow of fluid from the reservoir. When the device is thus regulated the operation becomes automatic and the body may be left by the operator with the assurance that it will be efficiently embalmed. In cases where it is difficult to force the embalming fluid through the body by gravity alone the blow vessel 28 may be attached to the reservoir as shown in Fig. 2 and operated to accelerate the flow of fluid from the tank.

20 What is claimed is:

In an apparatus of the class described, the combination of a reservoir having an open lower end, a removable cap disposed across the open end of the reservoir, means for se-

curing the cap to the reservoir, said means comprising a strap having one end hinged to the reservoir and movable transversely of the latter against the outer face of the cap, a cam latch secured to the reservoir and operating through an opening in the free end of the strap to draw the latter against the outer face of the cap with relatively great pressure, a tube passing centrally through the cap one end of which is disposed within the reservoir and terminates a short distance from the top of the latter, while the other end thereof projects outwardly from the other end thereof, and an outwardly extending nipple secured to the cap and affording communication with the interior of the reservoir.

In testimony whereof, I affix my signature, in presence of two witnesses.

LEVEY McCOY.
